UNITED STATES PATENT OFFICE

STANHOPE W. NIXON, OF PHOENIX, ARIZONA, ASSIGNOR TO NIXON NITRATION WORKS,
OF NIXON, NEW JERSEY, A CORPORATION OF NEW JERSEY

DESIGN FOR A GOLF TEE

Application filed November 24, 1931. Serial No. 41,847. Term of patent 7 years.

To all whom it may concern:

Be it known that I, STANHOPE W. NIXON, a citizen of the United States, and a resident of Phoenix, county of Maricopa, and State of Arizona, have invented a new, original, and ornamental Design for a Golf Tee, of which the following is a specification, reference being had to the accompanying drawings, forming a part thereof.

Figure 3 is a front view;
Fig. 4 is a top plan view, and
I claim:
The ornamental design for a golf tee, as shown.
In testimony whereof I affix my signature.

STANHOPE W. NIXON.
